SEWING MACHINE

John Theodore Cuthbertson, Philadelphia, Pa.

Application October 3, 1951, Serial No. 249,458

2 Claims. (Cl. 112—218)

1

This invention relates to sewing machines. More specifically, it is concerned with sewing machines useful in attaching ornamenting threads or braids to outline or otherwise embellish design figures, for example, on stoles, chalices and altar covers, ecclesiastical garments and like articles used in churches and other religious establishments.

The chief aim of my invention is to provide simple and inexpensive means, in the form of an attachment for a sewing machine of the type referred to, whereby one or more ornamenting threads are directed from a source or sources of supply toward the stitch forming instrumentalities in such a way that said threads are attached to base fabric with concealment of the stitching except for longitudinally-spaced transverse overlapping binding portions of the needle thread.

Other objects and attendant advantages will appear from the following detailed description of the attached drawings wherein:

Fig. 1 is a view in front elevation of a sewing machine conveniently embodying my invention.

Fig. 2 is a fragmentary view of the machine, partly in front elevation and partly in longitudinal section, drawn to a longer scale.

Fig. 3 is a fragmentary view in transverse section taken as indicated by the angled arrows III—III in Fig. 2.

Fig. 4 is a fragmentary view in horizontal section taken as indicated by the angled arrows IV—IV in Fig. 2.

Fig. 5 is a perspective view showing how the ornamenting threads are sewed to the fabric by the machine; and

Fig. 6 is a perspective view of the presser foot of the machine.

The knitting machine herein illustrated is, generally speaking, of well known construction in that it has a bed plate 10 and an over-reaching arm 11 with a terminal head 12. The needle bar, indicated at 13, which carries the sewing needle 14, is constrained to up and down movement in a frame 15 pivoted at 16 within the head 12. Needle bar 13 reciprocated endwise through a link 17, by a crank 18 at one end of a drive shaft 19 journalled in suitable bearings within overhanging arm 11. Shaft 19 protrudes from arm 11 beyond the supporting column 20 of the latter and is provided with the usual hand wheel 21, and also with a pulley 22 for power actuation, through a belt 23, from a suitable prime mover such as an electric motor (not shown). Frame 15 is oscillated about its fulcrum 16 through a horizontal link 24, for impartation of lateral vibrating movements to needle 14, by mechanism

2

concealed within the hollow of overhanging arm 11 and actuated from shaft 19 in a well known manner. Cooperative with needle 14 in stitch formation is a looper 25 of the rotary type which is secured to one end of a transversely-extending shaft 26 journalled beneath bed plate 10. Incident to the sewing, the fabric material M being operated upon is intermittently advanced on bed plate 10 relative to needle 14 by a feed dog 27 which is connected to a rocker 28, and reciprocated, through an arm 29, by an eccentric 30 on a longitudinally extending shaft 31 beneath said bed plate driven through connections (not shown), within the standard 20 from shaft 19. 15 Rotary movement is imparted to looper shaft 26 from shaft 31 through a pair of miter gears 32 and 33. Opposing the feed dog 27 from above is a centrally open presser foot 35 which is pivoted at 36 to a bracket arm 37 at the bottom of the presser bar 38, the latter being spring biased as usual and constrained to up and down movement in the needle head 12. Sewing thread T is supplied to needle 14 from a spool S on the top of overhanging arm 11 under control of the take-up indicated at 39.

To adapt a sewing machine, such as above briefly described, for the purposes of my invention, I have provided the presser foot 35 centrally of its front or advance end, with a tubular guide 40, for directing the comparatively heavy ornamenting threads T¹, T² which are to be attached to the material M relative to the stitch forming instrumentalities of the machine. It will be noted that the guide tube 40 is inclined at an acute angle toward bed plate 10, and that the passage therethrough is transversely elongate. As a consequence, the threads T¹, T² are accurately guided, side by side, downward on to bed plate 10 along a line medially of the points of penetration of the material M by the laterally-vibrated needle 14 as best shown in Fig. 4, and overlapped at longitudinal intervals by the cross-wise portions only of the sewing thread T at the stitches S. During the sewing, the material M, in being advanced in the direction of the arrow in Fig. 4, is manipulated in the illustrated instance so that the ornamenting threads T¹, T² outline a pre-cut padded design piece P, and at the same time secure said piece to the base material M.

The ornamenting threads T¹, T² are supplied from spools S¹, S² which, in accordance with my invention, are supported at an elevation by an upright stand 42 positioned at a substantial distance from the sewing machine, upon the work table 43 whereon the machine is sustained. As

shown, stand 42 has a base 45 wherein is anchored a rod 46 of stout wire the upper end portion 46a of which is bent forwardly at an angle toward the machine. Adjustably secured to the inclined portion 46a of rod 46 by a screw 47, is a U-shaped member 48 whereof the extremities 48a and 48b serve, with said inclined portion 46a, as axes by which spools S¹ and S² containing supplies of the ornamenting threads are supported for free rotation to permit withdrawal of said threads freely from them laterally. While I have shown spools S¹ and S² as impaled respectively on stem 46 and on extremity 48a of cross arm 48, a third spool may be used on extremity 48b if desired and its thread directed to the sewing machine with the threads T¹, T². For the better control of the ornamenting threads en route to the machine, I have shown an auxiliary guide 49 which is secured to the sewing head 12 and which has an angularly bent tri-apertured end portion 49a disposed in proximity to guide tube 40 on presser foot 35 at a slight elevation above the latter.

From the foregoing, it will be seen that I have provided a simple and inexpensive attachment whereby ornamenting threads are controlled en route to the stitch-forming instrumentalities of the sewing machine and directed, side by side, so as to be attached to the base material M and overlapped at spaced intervals longitudinally by the cross portions only of the sewing thread with the stitching otherwise substantially concealed.

Having thus described my invention, I claim:

1. In a sewing machine having a bed plate and a table therefor an overhanging arm with a terminal head for supporting an endwise-reciprocated laterally-vibrated sewing thread-carrying needle, a cooperating thread-carrying looper, a feeding element for intermittently advancing fabric laterally of the bed plate beneath the arm, and a presser foot to cooperate with the feeding

element, the combination of a stand mounted on the table substantially in line with the arm of the machine and beyond the head thereof, said stand being in the form of a post with its distal end portion inclined toward the needle head of the machine; a bracket affixed to the distal end portion of the post and provided with pins at a corresponding inclination upon which individual spools for plural ornamenting threads are impaled; and a straight transversely-flattened guide tube on the presser foot, said tube being tapered and downwardly sloped toward the bed plate with its large end uppermost to receive the ornamenting threads in straight lines from the supply spools substantially at right angles to the axes of said spools, and to converge said threads into direct laterally abutting relation for delivery in a horizontal path side by side medially of the points of penetration of the fabric by the needle so as to be overlapped at longitudinally-spaced intervals by the sewing thread.

2. The invention according to claim 1, further including a pendent finger affixed to the needle head of the machine and having, at its distal end, spaced guide eyes for maintaining the ornamenting threads definitely separated at a distance slightly in advance of the tubular guide on the presser foot.
